UNITED STATES PATENT OFFICE

DAVID W. HABER, OF BRONX, NEW YORK

DESIGN FOR AN ASH TRAY OR SIMILAR ARTICLE

Application filed February 6, 1932. Serial No. 42,759. Term of patent 7 years.

To all whom it may concern:

Be it known that DAVID W. HABER, citizen of the United States, and resident of Bronx, in the county of Bronx and State of New York, has invented a new, original, and ornamental Design for an Ash Tray or Similar Article, of which the following is a specification, reference being had to the accompanying drawing, forming part thereof, in which, The figure is a perspective view of an ash tray embodying my new design.

I claim:

The ornamental design for an ash tray or similar article, substantially as shown.

Dated, February 5th, 1932.

DAVID W. HABER.
